UNITED STATES PATENT OFFICE

95,516

DESIGN FOR A MASSAGE APPLICATOR

Anton Kretschan, Chicago, Ill.

Application April 28, 1934, Serial No. 51,580

Term of patent 7 years

To all whom it may concern:

Be it known that I, Anton Kretschan, a citizen of the United States, residing at Chicago, in the county of Cook and State of Illinois, have invented a new, original, and ornamental Design for Massage Applicators, of which the following is a specification, reference being had to the accompanying drawing, forming part thereof.

Figure 1 is a top view, Figure 2 is a front view and Figure 3 is a side view of a massage applicator showing my new design.

I claim:

The ornamental design for a massage applicator, as shown.

ANTON KRETSCHAN.
